(57) CLAIM

The ornamental design for an elevated dumbbell holder showing my new design.

DESCRIPTION

FIG. 1 is a perspective view of an elevated dumbbell holder showing my new design, wherein the broken line showing of the environmental structure is for illustrative purposes only and forms no part of the claimed design.

FIG. 2 is a perspective view thereof;

FIG. 3 is a perspective view thereof, taken generally from the opposite side of FIG. 2;

FIG. 4 is a perspective view thereof, taken generally oppositely to FIG. 2;

FIG. 5 is a perspective view thereof, taken generally from the opposite side of FIG. 4;

FIG. 6 is a top plan view thereof;

FIG. 7 is a front elevational view with the opposite side being a mirror image thereof;

FIG. 8 is a side elevational view with the opposite side being a mirror image thereof; and,

FIG. 9 is a bottom plan view thereof.
